UNITED STATES PATENT OFFICE.

MERRITT ISAAC TUTTLE, OF FROMBERG, MONTANA, AND LEWIS L. HILL, OF YELLOWSTONE PARK, WYOMING.

WATER-POWER MOTOR.

Application filed July 6, 1921. Serial No. 482,732.

To all whom it may concern:

Be it known that we, MERRITT I. TUTTLE and LEWIS L. HILL, citizens of the United States, and residents, respectively, of Fromberg, in the county of Carbon and State of Montana, and of Yellowstone Park, State of Wyoming, have invented a new and Improved Water-Power Motor, of which the following is a full, clear, and exact 10 description.

This invention relates to improvements in water power motors, particularly to a motor wherein a plurality of gravity operated balancing tanks are utilized to transmit motion to a power shaft. An object of the invention is to provide an improved mechanism for automatically controlling the flow of water into the tanks and a novel mechanism for automatically discharging the 20 water from the tanks.

A further object is to provide a plurality of balancing tanks so arranged that the weight of a descending filled tank operates to restore an empty tank to a position where 25 it may be refilled.

A still further object is to suggest one convenient means of operatively connecting the balancing tanks to a power shaft.

Another object is to provide a water motor 30 wherein a maximum amount of energy is developed with a minimum amount of water.

Still another object is to provide a water motor, which will be simple and practical in construction, strong, durable and efficient 35 in use, which may be quickly repaired, and which will be comparatively inexpensive to manufacture.

With these and other objects in view, the invention consists in certain novel features 40 of construction and combinations and arrangements of parts as will be more fully hereinafter described and pointed out in the claims.

In the accompanying drawings:—

Figure 1 is a view in side elevation of our 5 improved water motor;

Figure 2 is a top plan view thereof, with parts broken away for clearness;

Figure 3 is a view in front elevation;

Figure 4 is a reduced diagrammatic view 10 illustrating a plurality of balancing tanks operated from a single reservoir and coupled to operate stroke pumps for irrigation purposes; and

Figure 5 is an end view of Figure 4.

Referring in detail to the drawings, 1

represents a rectangular frame supported above the ground by suitable uprights 2. Adjacent the center of the frame 1, certain of the uprights 2 extend above the frame, 60 as indicated at 3, and serve to support a pair of transverse beams 4. Diagonal braces 5 connect the uprights 2.

Adjacent the rear end of the frame 1, a water tank or reservoir 6 is supported 65 upon suitable means 7. 8 represents an inlet spout or trough for the reservoir 6. A pair of water outlets are provided in the forward face of the reservoir 6 and are controlled by vertical slidable gates 9.

A pair of transverse frame bars 10 are secured below the frame 1. Between these frame bars and extending in the same plane, a rocking beam 11 is pivoted at its center 70 on a pin or bolt 12.

Forwardly of the frame bars 10 and located above these frame bars is a shaft 13 journaled in a pair of the uprights 2. 14, 14 represent a pair of balancing tanks. These tanks include at this rear ends relatively narrow shallow troughs or inlets 15 and at their forward ends gradually increase in width and depth. Covers 16 are provided on the forward ends of the tanks and the tanks are pivoted adjacent their rear 85 ends in any suitable manner upon the shaft 13. It will of course be understood that the tanks swing in planes transverse to the shaft upon which they are pivoted.

The lower portions of the forward ends 90 of the tanks 14 are provided with doors 17, hinged at their upper edges, as indicated at 18. These doors are normally retained in closed position by weighted locking arms 19 pivoted on the bottom of the tanks 14 95 and including hooked ends 20 engageable with the free lower edges of the doors 17 to retain the doors against opening.

The pivotal movement of the tanks in one direction is limited by a cross bar 21 engageable under the free ends of the troughs 15. The pivotal movement of the tanks in the other direction is limited by a trip 22 secured to the diagonal braces 5 and engageable with the weighted ends of the locking arms 19 to trip these arms and permit the water pressure in the tanks 14 to open 105 the gates 17.

The doors 17 are positively locked during the upward movement of the forward ends 110 of the tanks 14 by springs 23, with which these doors have wiping engagement. The

2
hooked ends 20 of the locking arms 19 include cam faces 24 over which the free edges of the doors 17 ride when actuated by the springs 23.

5 The troughs 15 are operatively connected to opposite ends of the rocking beam 11 in any approved manner. For the purposes of illustration, I have shown balls 25 carried by opposite ends of the rocking beam 10 11, balls 26 depending from the troughs 15 and sleeves 27 interposed between the ends of the beam 11 and the troughs 15 and having sockets 28 in their ends receiving the balls. The sleeves 27 are preferably 15 formed from a pair of castings joined together and the sockets 28 are of sufficient size to almost completely embrace the balls 25 and 26 so that the ends of the beam 11 are coupled with the troughs 15 for positive 20 movement in either direction.

Pairs of longitudinal frame bars 29 have their ends supported upon the cross beams 4 and are located directly over the troughs 15. Levers 30 have their forward ends 25 pivoted between the frame bars 29, as indicated at 31. Relatively short levers 32 are also pivoted between the frame bars 29 at their intermediate portions on pins or bolts 33 and are engageable under the levers 30 30 to raise the free ends of the same. The ends of the levers 32 which are engageable under the levers 30 are rounded or beveled, as indicated at 34, and at their other ends, the levers 32 carry depending stirrups 35 35 adapted to receive the troughs 15. Links 36 connect the free ends of the levers 30 with the sliding gates 9 in the forward end of the reservoir 6.

The frame bars 10 are supported by pairs 40 of upright members 37 and between these uprights, a crank shaft 38 is journaled in sectional bearings 39, the crank shaft extending transversely of the frame 1 and being located in parallelism with and directly 45 below the rocking beam 11. Crank arms 40 are provided on the crank shaft and links 41 connect the crank arms 40 with the ends of the rocking beam 11. A pulley such as 42 may be provided on the end of the shaft 50 38 for the attachment of a belt or similar power transmitting device (not shown).

The operation of the motor is as follows:—

To start the motor, the tanks are located 55 in substantially the position shown in Figure 1, one of the tanks being located in horizontal position with the trough 15 resting on the bar 21 and the other tank swung on its axis until its forward end is stopped 60 on its axis by the trip 22. The trough 15 which is in horizontal position is resting on one of the stirrups 35 and has operated through the medium of the stirrup 35, levers 32 and 30 and link 36 to raise one of the sliding gates 9, so 65 that a flow of water is had from the reservoir

into this tank. As the water flows into this tank, the forward end of the tank will descend by gravity and the trough 15 will operate through the medium of the ball and socket connection 25, 26 and 27 to oscillate 70 the rocking beam 11. As the trough 15 is raised, the gate 9 will close by gravity cutting off a flow of water. By the time this tank has reached the limit of its downward movement and the trip 22 operates through 75 the medium of the locking arm 19 to discharge the water from the forward end of the tank, the other tank will be in horizontal position and receiving water. It will be apparent that by virtue of their connection 80 with the rocking beam 11, the descending tank will always operate to raise the empty tank into position for refilling. As the beam 11 oscillates or rocks about its pivotal point, it will operate the shaft 38 through the 85 medium of the links 41 and crank arms 40.

In Figures 4 and 5, I have illustrated somewhat diagrammatically a reservoir 43 and shafts 44 on opposite sides of the reservoir. A plurality of balancing tanks 45 and 46 pivot on the shafts 44. Each one of the tanks 45 is coupled to a tank 46 on the opposite side of the reservoir by links 47 and a rocking beam 48 pivoted on a central support 49 which supports the reservoir. The ends of the rocking beam 48 are operatively connected to stroke pumps 50. The depression of a tank 46 operates to bring the tank 45 into position for filling, as seen clearly in Figure 5. The principal use of the tanks will be for operating stroke pumps for irrigation purposes and I have merely illustrated one convenient means for operatively coupling a plurality of tanks to drive the pumps. The number of tanks used, however, or the particular means of connecting them to the pumps is immaterial to this invention, since the arrangement of the tanks might be infinitely varied without departing 105 from the scope of the claims.

Various slight changes and alterations might be made in the general form and arrangement of the parts described without departing from the invention and hence we do not wish to limit ourselves to the precise 115 details set forth, but shall consider ourselves at liberty to make such slight changes and alterations as fairly fall within the spirit and scope of the appended claims.

We claim:

1. A water motor including a frame, a reservoir associated with the frame, a pair of trough-shaped balancing tanks journaled intermediate of their ends on a common axis to swing longitudinally of the frame, means whereby the gravitational depression of one tank operates to move the other tank into position for filling, said means comprising a rocking beam and links having ball and socket connections with the ends of 120 125 130

the rocking beam and the bottoms of the tanks.

2. A water motor including a frame, a reservoir associated with the frame, a pair of balancing tanks journaled on a common axis to swing longitudinally of the frame, means whereby the gravitational depression of one tank operates to move the other tank into position for filling, said means comprising a rocking beam and flexible links connecting the ends of the rocking beam with the ends of the tanks, gates controlling the flow of water from the reservoir into the tanks, frames located above the tanks, levers pivoted in the frames, stirrups attached to levers and receiving the ends of the tanks, means whereby depression of the stirrups opens the gates.

3. A water motor including a frame, a reservoir associated with the frame, a pair of balancing tanks journaled intermediate of their ends on a common axis to swing longitudinally of the frame, means whereby the gravitational depression of one tank operates to move the other tank into position for filling, said means comprising a rocking beam and flexible links connecting the ends of the rocking beam with the bottoms of the tanks, said tanks including relatively narrow shallow troughs at one end into which water is introduced and relatively deep wide receptacles at their other ends, doors hinged to the receptacle and normally closing said receptacles, means whereby gravitational depression of said receptacles opens said doors.

4. A water motor including a frame, a reservoir associated with the frame, a pair of balancing tanks journaled on a common axis to swing longitudinally of the frame, means whereby the gravitational depression of one tank operates to move the other tank into position for filling, said means comprising a rocking beam and flexible links connecting the ends of the rocking beam with the ends of the tanks, said tanks including relatively shallow troughs at one end into which water is introduced and relatively deep wide receptacles at their other ends, doors normally closing said receptacles, means whereby gravitational depression of said receptacles opens said doors, said means including weighted pivoted arms normally closing said doors, and means for tripping said arms when the receptacles are depressed.

5. A water motor including a frame, a reservoir associated with the frame, a pair of balancing tanks journaled on a common axis to swing longitudinally of the frame, means whereby the gravitational depression of one tank operates to move the other tank into position for filling, said means com-

prising a rocking beam and flexible links connecting the ends of the rocking beam with the ends of the tanks, said tanks including relatively shallow troughs at one end into which water is introduced and relatively deep wide receptacles at their other ends, doors normally closing said receptacles, means whereby gravitational depression of said receptacles opens said doors, said means including weighted pivoted arms normally closing said doors, and means for tripping said arms when the receptacles are depressed, and means for positively locking the doors upon upward movement of the receptacles, said means including springs having wiping engagement with the doors.

6. A device of the character described in claim 5 and in which the weighted arms include hooked ends retaining the doors in closed position, said hooked ends including cam faces over which the free edges of the doors ride to closed position when actuated by the springs.

7. In a water motor, a pair of balancing tanks pivoted on a common axis and swinging in a transverse plane thereto, a rocking beam, a power shaft, means whereby pivotal movement of the tanks oscillates the rocking beam, means whereby oscillation of the rocking beam rotates the shaft, said first mentioned means including a ball carried by one end of each tank, balls carried by the ends of the rocking beam, split sleeves interposed between the ends of the beam and the ends of the tanks, and including sockets at their ends receiving the balls.

8. In a water motor, a reservoir having a pair of valve controlled outlets, a pair of tanks pivoted intermediate of their ends and adapted to discharge their contents when tilted, a pair of pivoted levers, means carried by the levers with which the tanks have removable connection, a second pair of pivoted levers, operated by the first pair of levers, and means for operating the valves of the said outlets from the second pair of levers.

9. In a water motor, a reservoir having a pair of outlets, sliding gates for controlling said outlets, a pair of tanks pivoted intermediate of their ends, and adapted to discharge their contents when tilted, a pair of levers pivoted at one end, stirrups carried by the levers and receiving one end of the tanks when in horizontal position, a second pair of levers pivoted intermediate their ends and having one end engaging the first named levers, and links connecting the second pair of levers with the said gates.

LEWIS L. HILL.
MERRITT ISAAC TUTTLE.
